UNITED STATES PATENT OFFICE.

JOHN T. QUAYLE, OF PROVIDENCE, RHODE ISLAND.

DESIGN FOR A BREASTPIN.

SPECIFICATION forming part of Design No. 14,480, dated December 11, 1883.

Application filed July 23, 1883. Term of patent 3½ years.

To all whom it may concern:

Be it known that I, JOHN T. QUAYLE, of the city and county of Providence and State of Rhode Island, have invented a new and original Design for Breastpins; and I do hereby declare the following specification, taken in connection with the accompanying drawings, forming a part of the same, to be a description thereof.

10. This design consists in a breastpin having a body portion which is rectangular in cross-section, and ornamental tips or ends resembling acorns in outline, as will hereinafter appear.

Referring to the drawings, Figure 1 shows 15 a top or face view of the breastpin embodying the design. Fig. 2 shows a side view of the same. Fig. 3 shows a cross-section through the body portion.

As particularly shown in Fig. 3, the body A 20 of the breastpin is rectangular in cross-section, or has its sides a' a' at right angles to its face a .

The ornamental tips or ends B somewhat resemble acorns in appearance or outline, and project from the ends of the body A. These ends may be plain, or may be ornamented in 25 any preferred manner.

The body A may be ornamented by engraving or chasing, and may have ornamental pieces or members secured thereto, if desired, the ornamentation of the body or the ends by 30 engraving, &c., forming no part of the design.

What I claim, and desire to secure by Letters Patent, is—

The design for a breastpin, consisting of the body A, rectangular in cross-section, and the 35 tips or ends B, resembling acorns in outline, substantially as described and shown.

JOHN T. QUAYLE.
